PLURAL SURFACE SLEEVE BOARD

David F. Fletcher, Olyphant, Pa.

Application April 12, 1951, Serial No. 220,651

1 Claim. (Cl. 38—135)

1

This invention relates to ironing equipment, and more particularly to a board for use in ironing or pressing sleeves on articles of clothing.

The object of the invention is to provide a sleeve board which will facilitate the ironing of sleeves on dresses, shirts or other clothing, the board of the present invention accommodating sleeves of various sizes.

Another object of the invention is to provide a sleeve board which includes a pair of board members that enable sleeves of different sizes to be ironed, the device of the present invention being constructed so that the entire length of the support member can be utilized.

A further object of the invention is to provide a sleeve board which is extremely simple and inexpensive to manufacture.

Other objects and advantages will be apparent during the course of the following description.

In the accompanying drawings forming a part of this application, and in which like numerals are used to designate like parts throughout the same:

Figure 1 is a side elevational view of the sleeve board constructed according to the present invention;

Figure 2 is a side elevational view of the sleeve board, showing the parts positioned so that the other support member can be utilized;

Figure 3 is a top plan view of the sleeve board with the parts positioned as shown in Figure 2;

Figure 4 is a sectional view taken on the line 4—4 of Figure 2;

Figure 5 is a sectional view taken on the line 5—5 of Figure 1;

Figure 6 is a sectional view taken on the line 6—6 of Figure 4;

Figure 7 is a fragmentary plan view showing certain constructional details of the device;

Figure 8 is a sectional view taken on the line 8—8 of Figure 7.

Referring in detail to the drawings, the numeral 10 designates a vertically disposed body member which may be fabricated of any suitable material, and secured to one end of the body member 10 in any suitable manner, as by nails or screws, is a first support member 11, Figure 1. The support member 11 has its free end shaped arcuately, as at 12, Figure 3, so that the sleeve of a shirt, dress or other article of clothing can be readily slipped over this support member and ironed or pressed.

The sleeve board of the present invention further includes a hinge 14 which serves to hingedly connect a second support member 15 to the oppo-

2

site end of the body member 10. The other end of the support member 15 is curved or shaped arcuately, as at 16, Figure 3. The second support member 15 is also adapted to have a sleeve of a shirt or dress slipped thereover, so that such sleeve can be readily ironed, the pair of support members accommodating sleeves of different sizes.

A spring member 17 has one end secured to the body member 10 by suitable securing elements, such as screws or rivets 18, Figure 2, while the other end of the spring member 17 bears against or abuts the support member 15 for normally urging the support member 15 and support member 11 apart. Thus, depending upon which of these support members is being used, the sleeve can be readily slipped over the support member.

Arranged in spaced relation with respect to the body member 10 is a U-shaped yoke 19 which may be fabricated of spring metal. The yoke 19 includes a web 20, and spaced parallel spring legs 21, each of the spring legs 21 terminating in a transverse flange or foot 22.

The support member 11 is provided with a pair 25 of spaced slots 23, and arranged over a portion of each of the slots 23 is a plate 24, the plate 24 being secured to the support member 11 by suitable securing elements, such as nails or screws 25. The other support member 15 is provided with a similar pair of slots 26, and a plate 27 extends over a portion of each of the slots 26, the plates 27 being secured to the support member 15 by suitable securing elements, such as nails or screws 28. Depending upon which of the support members 11 or 15 are being used, the feet 22 of the yoke 19 can be arranged in engagement with the slots 26 or 23, whereby the yoke 19 will provide a support for the support member when the sleeve is being ironed.

The sleeve board of the present invention may be arranged as shown in either Figure 1 or Figure 2. With the board arranged as shown in Figure 1, the spring 17 will normally urge the support member 15 into the solid line position 40 of Figure 1, so that a sleeve of a shirt or dress can be conveniently slipped over the support member 15. Then said sleeve can be ironed or pressed with a conventional iron. If it is desired to use the other support member 11, as when a sleeve of a different size is to be pressed, then the assembly is turned over so that the member 15 is on the bottom, while the member 11 is on the top, as shown in Figure 2. Also, the yoke 19 is disconnected from the support member 11 by 45 squeezing together the spring legs 21 from the

solid line position shown in Figure 4 to the dotted line position shown therein, so that the feet 22 can be removed from the slots in the support member. When the board is being used as shown in Figure 2, the feet 22 are engaged in the slots 26 in the support member 15. The yoke 19 thus provides a support for the particular support member being used, and the spring member 17 will likewise urge the support member 11 from the dotted line position shown in Figure 2 to the solid line position of Figure 2, so that a sleeve can be readily slipped over the support member 11.

Since the spring member 17 urges the support member being used away from the yoke 19, then the entire length of the support member can be utilized, while ironing a sleeve. The yoke 19 is interchangeable so that its feet fit in the slots in the support member 11 or the support member 15. When the pressure of the spring legs 21 is released, the resiliency of these spring legs will cause the legs to spread apart so that the yoke will not accidentally become disengaged from the slots. The spring 17 urges the support member being away from the yoke 19 when the person removes the iron from the board, permitting the user to slide or turn the sleeve to any desired position.

What is claimed is:

In an ironing board for use in ironing sleeves, a vertically disposed body member, a first support member having one end secured to said body member and its other end shaped arcuately, a second support member hingedly connected to said body member and provided with an arcuate end, a spring member secured to said body member and abutting said second support member, each of said support members being provided with a pair of slots, a U-shaped yoke interposed between said pair of support members and including a web, and a pair of spring legs terminating in transverse feet for selectively seating in said slots.
